UNITED STATES PATENT OFFICE.

ALLEN BURCH, OF AMORY, MISSISSIPPI, ASSIGNOR OF ONE-HALF TO WALTER W. FENNELL, OF AMORY, MISSISSIPPI.

FIRE-SCREEN.

1,225,762.

Specification of Letters Patent. Patented May 15, 1917.

Application filed August 18, 1915. Serial No. 46,159.

To all whom it may concern:

Be it known that I, ALLEN BURCH, a citizen of the United States, residing at Amory, in the county of Monroe and State of Mississippi, have invented a new and useful Fire-Screen, of which the following is a specification.

This invention relates to fire screens, one of its objects being to provide a device of 10 this character which can be adjusted readily to fit open fireplaces of different widths and which has combined with it a panel adapted to be used either as a front section of the screen or else as a shelf on which utensils 15 may be placed when it is desired to cook over the fire back of the screen.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 25 within the scope of what is claimed, without departing from the spirit of the invention.

In the accompanying drawings the preferred form of the invention has been shown.

30 In said drawings:—

Figure 1 is a front elevation of the fire screen.

Fig. 2 is a plan view thereof.

Fig. 3 is a rear elevation.

35 Fig. 4 is a section on line A—B Fig. 3 and showing the adjustable panel swung inwardly to position for use as a shelf.

Referring to the figures by characters of reference 1 designates standards having upper and lower longitudinal slots 2 and extending rearwardly from the lower portion of each standard is an arm 3 terminating at its back end in a foot 4 so that the standard is thus allowed to stand in a substantially upright position. The arms 3 constitute supports for logs or other fuel.

Arranged in front of each of the standards 1 is a panel 5 having a foot 6 at its outer end and an inwardly extending flange 7 at said end, there being upper and lower blocks 8 at the inner end of the panel and upon the back face thereof. Extending through the flanges 7 and blocks 8 of the two panels 5 and through the slots 2 in the 55 standards 1 are upper and lower connecting

rods 9 preferably screw threaded throughout the length thereof. Nuts 10 engage the ends of the rods and bear against the outer sides of the flanges 7 and by means of these nuts the two panels 5 can be adjusted toward each other. Additional nuts 11 are mounted on the rods and bear against the blocks 8 and by means thereof the panels 5 can be adjusted away from each other. Nuts 10 and 11 on the two rods coöperate to hold 60 the panels normally against movement relative to each other. Nuts 12 are mounted on the rods at opposite sides of the standards 1 and serve to clamp said standards so as to hold them against movement independently 65 of the rods. By loosening the nuts the standards can be adjusted upwardly or downwardly relative to the panels 5.

Pivots mounted on the upper rod 9 at points between the inner ends of the panels 5 are ears 13 extending inwardly from the upper portion of a central panel 14 which is adapted to lap the inner end portions of the panels 5 and to be supported in front thereof as shown particularly in Fig. 2. 70 Nuts 15 engage the upper rod 9 between the ears 13 and constitute means for holding the central panel against lateral movement along the rod. It will be obvious that by constructing the screen as described the same 75 can be adjusted readily to fit into fireplaces of different widths and by adjusting the standards 1 vertically relative to the panels 5, the same can be adjusted to rest upon surfaces elevated above or lowered below those 80 surfaces on which the legs 6 are mounted. This is especially useful where the end portions of the screen are adapted to rest on the floor while the standards are adapted to 85 rest upon elevated tiles.

Should it be desired to use the screen as a support for utensils the central panel 14 of the screen can be swung upwardly and backwardly until one longitudinal edge thereof is brought against the back faces 90 of the panels 5, as shown in Fig. 4, whereupon the intermediate panel 14 will be held in a substantially horizontal position. Thus utensils can be supported over the logs or other fuel.

Extending inwardly from the back face of each panel 5 near its flange 7 are loops 16 preferably arranged in pairs, said loops being located above supporting blocks 17 on the panels 5. Thus various implements, 100 105 110

such as tongs, pokers and the like may be inserted downwardly through the loops and supported on the blocks 17.

What is claimed is:—

- 5 1. A fire screen including spaced front panels, threaded rods connecting the panels and constituting adjustable connections therebetween, said rods extending across the space between the panels, a central panel, 25 ears extending therefrom and engaging one of the rods to support the central panel normally in front of the inner end portions of the side panels, the upper edge of the middle panel coöperating with the back faces of the side panels to support the middle panel 30 in a substantially horizontal position back of the side panels and irrespective of the extent of adjustment of said side panels relative to each other.
- 10 15 20 2. A fire screen including spaced front panels, threaded rods connecting the panels and constituting adjustable connections

therebetween, said rods extending across the space between the panels, a central panel, ears extending therefrom and engaging one of the rods to support the central panel normally in front of the inner end portions of the side panels, the upper edge of the middle panel coöperating with the back faces of the side panels to support the middle panel 30 in a substantially horizontal position back of the side panels and irrespective of the extent of adjustment of said side panels relative to each other, and arms adjustably connected to the rods and supporting feet extending from the arms. 35

In testimony that I claim the foregoing as my own, I have hereto affixed my signature in the presence of two witnesses.

ALLEN BURCH.
